US0D1067074S

(12) **United States Design Patent** (10) **Patent No.:** **US D1,067,074 S**
(45) **Date of Patent:** **** Mar. 18, 2025**

(54) **WIRE LOCATOR**

(71) Applicant: **TEMPO COMMUNICATIONS INC.**,
Vista, CA (US)

(72) Inventors: **Curtis C. Taylor**, Vista, CA (US);
Kenneth O. Stark, San Marcos, CA
(US)

(73) Assignee: **TEMPO COMMUNICATIONS INC.**,
Vista, CA (US)

(**) Term: **15 Years**

(21) Appl. No.: **29/877,213**

(22) Filed: **Jun. 3, 2023**

(51) LOC (15) Cl. **10-04**

(52) U.S. Cl.

USPC **D10/78**; D10/96

(57) **CLAIM**

The ornamental design for a wire locator, as shown and described.

DESCRIPTION

FIG. 1 is an isometric view of a wire locator;

FIG. 2 is a rear view thereof;

FIG. 3 is a front view thereof;

FIG. 4 is a left side thereof;

FIG. 5 is a right view thereof;

FIG. 6 is a top view thereof; and,

FIG. 7 is a bottom view thereof.

The broken lines in the drawings illustrate portions of the wire locator that form no part of the claimed design.

1 Claim, 6 Drawing Sheets
